FIG. 6.

Inventor

BENNETT GROTTA,

By *Samuel Herrick*,

Attorney

UNITED STATES PATENT OFFICE.

BENNETT GROTTA, OF TAMAQUA, PENNSYLVANIA, ASSIGNOR TO ATLAS POWDER COMPANY, OF WILMINGTON, DELAWARE, A CORPORATION OF DELAWARE.

DEVICE FOR INSURING UNIFORM PRESSURE UPON EXPLOSIVE CHARGES.

Application filed December 6, 1924. Serial No. 754,353.

To all whom it may concern:

Be it known that BENNETT GROTTA, citizen of the United States, residing at Tamaqua, in the county of Schuylkill and State of Pennsylvania, have invented certain new and useful Improvements in Devices for Insuring Uniform Pressure Upon Explosive Charges, of which the following is a specification.

10 My invention relates to an improvement in equipment commonly used for the manufacture of detonators and other articles which are similarly assembled and it has for its primary object the provision of improved means for insuring uniform pressure upon the explosive charges of such detonators.

15 In the manufacture of detonators it is customary to deposit the explosive charge used into a large number of detonator shells or metal casings in a single operation, and then remove the rack containing the charged shells to a press where pressure is applied simultaneously to all of the 20 charges by means of numerous metal punches, one of which enters the open end of each shell. These punches are mounted in a common press head and, with equal length punches, all charges are thus compressed to a uniform height.

25 It is a well known fact that by any of the methods which may be employed commercially an exactly uniform weight of charge cannot be deposited into the detonator shells. This is due to the fact that the charges are measured out by first filling a series of holes of the approximate cubical content desired, with the explosive used, and then permitting this charge to fall into 30 the shells. Variations in density of the explosive as well as variations in its flowing properties render it impossible to deliver charges of exactly uniform weight. As a consequence, with the usual methods of 35 pressing, the under-weight charges are under-pressed while the over-weight charges are over-pressed.

40 The over-pressed charges may result in distorted and bulged detonator shells and 45 there is also the possibility of rendering the charge non-explosive by over-compressing, as for example, "dead-pressed" fulminate charges. On the other hand, under-pressed charges are conducive to even greater ills,

The explosive charge, not being firmly pressed into a common mass, tends to loosen and subsequently fall out of the open end of the detonator shell. The presence of loose explosives in the metal containers in which detonators are usually packed constitutes a hazard in itself. Furthermore the possibility of detonators, from which part or all of the explosive charge has been lost, being used for initiating of other explosives, may result in the well known dangerous and costly misfires.

50 After extensive experimentation I have found that the above pressing difficulties may be obviated by the very simple device which is the subject of this patent application.

55 I have found that by providing a rack for the detonator shells which is so constructed that the shells are supported by some resilient material, such as rubber, 60 which, in turn, is supported by a solid backing, the pressure is equalized and all charges tend to be uniformly compressed.

65 One embodiment of my invention is illustrated in the accompanying drawings, 70 wherein—

75 Figure 1 is a perspective view of a rack constructed in accordance with the invention,

Figure 2 is a horizontal sectional view 80 illustrating the bottom plate in plan,

Figure 3 is a perspective view of a modified form of bottom plate, and

85 Figures 4, 5, and 6 are fragmentary sectional views through the recessed portions 90 of bottom plates like those illustrated in Figure 3, each of said Figures 4, 5 and 6 representing a different modification.

90 Like numerals designate corresponding parts throughout the several figures of the drawing.

95 The rack illustrated in Figures 1 and 2 constitutes a support and guide for maintaining the detonator shells in proper position during the time that the plungers are compressing the charges therein. This rack 100 comprises plates 5, 6 and 7. The plates 5 and 6 each have a plurality of aligned openings 8 formed therein through which the detonator shells pass, with their closed ends disposed downwardly. These closed ends rest upon a sheet of rubber, or like resilient material, indicated at 9, and in order to se- 105

surely hold this sheet of resilient material in place the plate 7 is preferably provided with upstanding edges 10. The several plates are held in properly spaced relation to each other in any desired manner, such, for example, as the provision of spacing blocks or lugs 11 at the corners of the plates. Instead of utilizing a single sheet of resilient material as illustrated in Figures 1 and 2, 10 to receive the lower ends of all of the detonator shells in the rack, I may employ an individual resilient backing for each detonator. This may be accomplished as indicated in Figure 3, wherein a plate 7^a corresponding to the plate 7, is provided with a plurality of recesses 12 corresponding in number to the openings formed in plates 5 and 6. These recesses 12 in plate 7^a are somewhat larger in area than the bases of 20 the detonators to be received therein, and these recesses receive the resilient material indicated at 13, 14 and 15 in Figures 3, 4, 5 and 6, respectively. In Figures 3 and 4, the recesses are illustrated as having straight 25 side walls. In Figure 5 the recess which has been designated 12^a is indicated as being of concave formation, while in Figure 6 the recess which has been designated 12^b is indicated as being of undercut formation in 30 cross section.

It is, of course, obvious that the closed end of the detonator shells will be supported by the resilient material in the bottom of the rack. It is also apparent that as the over-weight charges receive the desired degree of 35 compression the detonator shells containing these charges will tend to recede while the under-weight charges will still be supported by the resilient backing. In this manner 40 the over-weight charge is not over-pressed and the under-weight charge is not under-pressed.

I have found that by employing a rack equipped with a sheet of rubber one-eighth 45 inch thick, detonators having a variation of as much as 20% in weight of charge may be satisfactorily compressed with a single press.

I have also found that the desired effect 50 may be obtained by employing various resilient materials of different composition and thickness. The resilient material may

be cemented or vulcanized to the solid backing of the rack, or it may be left loose.

While I have described specifically how my invention may be applied in the manufacture of detonators it is apparent that it would have a similar application in the charging of any other explosive device wherein the density or compression of the explosive charge is an important factor. 60 Therefore, the employment of a resilient backing in the charging and pressing of any explosive into any type of shell or casing must be considered within the scope of my invention. 65

Having described my invention, what I claim is:

1. A device used in the pressing of explosive charges into shells, or other containers, consisting of a rack for supporting the 70 containers in a suitable position and a resilient backing on which the closed ends of the containers rest.

2. A device for equalizing the pressure applied to several detonator compositions by 75 a single press, which consists of a suitable rack fitted with a resilient backing on which the detonator shells are placed.

3. A device for equalizing the pressure applied to several detonator compositions by 80 a single press which consists of a suitable rack fitted with a backing of rubber on which detonator shells are placed.

4. A device for equalizing the pressure applied to several detonator compositions by 85 a single press, which consists of a suitable rack equipped with an individual backing of rubber of suitable resiliency for each detonator.

5. A device for equalizing the pressure 90 applied to several explosive charges, which consists of a support and guide for a plurality of containers of the explosive charges and means yieldable beyond a predetermined pressure, upon which the ends of said containers rest. 95

In testimony whereof he affixes his signature in the presence of two witnesses.

BENNETT GROTTA.
